United States Patent Office

Des. 184,961
Patented Apr. 21, 1959

184,961

WALL PLAQUE OR SIMILAR ARTICLE

August G. Reibling, Edgewood, R.I.

Application April 10, 1958, Serial No. 50,422

Term of patent 3½ years

(Cl. D29—23)

FIG. 1

FIG. 2

I claim:

The ornamental design for a wall plaque or similar article, as shown.
